INTERNAL COMBUSTION ENGINE

Noble P. Sherwood, Dallas, Tex., assignor to
Heuschober Engineering Corporation, Fort
Worth, Tex.

Application November 21, 1941, Serial No. 420,001

5 Claims. (Cl. 123—75)

This invention relates to internal combustion engines of the reciprocating type and in such connection it relates more particularly to the construction hereinafter shown and described.

One of the objects of the invention is the provision of a simple and inexpensive supercharged 4-cycle internal combustion engine designed to be operated on either compression ignition or spark ignition. In the construction of the engine hereinafter described in detail, the piston of the combustion chamber also provides a means for pressure supercharging.

Another object of the invention is the provision of means for a more thorough scavenging than any 4-cycle engine not equipped with separate scavenging pump.

A further advantage of the invention is that the piston operation does not set up pressure in the crank case of the engine.

Other objects and advantages of the invention will become apparent from a perusal of the following detailed description, taken in connection with the accompanying drawing, and in the drawing:

Figure 1 is a vertical sectional view of an internal combustion engine embodying the invention;

Figure 2 is a similar view to that of Figure 1, but on a smaller scale and illustrating a modification thereof; and

Figure 3 is a vertical sectional view of the invention on the same scale as that of Figure 2, and illustrating a variation in the form of a variable precompression chamber.

In accordance with the several views of the drawing, the engine consists of a cylinder 1 which is bolted or otherwise secured to its crank-case 2. The crank-case 2 is provided with a crank-shaft 3 which is operatively carried therein in the conventional manner. A piston 4 is slidably disposed in the cylinder 1 and operatively connected to the crank-shaft 3 by means of a crank-arm 5. The piston 4 is provided with a relatively long skirt 4a and the crank-arm 5 is disposed in the lower portion of the skirt of the piston, and connected thereto by a pin 6. This arrangement of the pin 6 in the skirt of the piston 4, permits the use of a disk 8 within the skirt of the piston and which serves as the base for an auxiliary chamber 7, the chamber being formed between the piston head and the disk 8 and within the confines of the piston skirt 4a.

The disk or partition 8 is rigidly held in position within the walls of the skirt 4a by means

of a plurality of arms 9 (only one of which is shown in Fig. 1) the lower ends of these arms projecting out of the crank-case end of the cylinder 1 and being secured to some portion of the crank-case 2 of the engine or cylinder block, such as shown in Figure 1. These arms 9 may be so arranged that they will not hinder the swing or movement of the crank-arm 5 during operation of the engine. In the construction shown the arms 9 are so formed as to extend through a slot 10 in the end of the cylinder 1. The top of the disk 8 may be so formed relative to the under-side of the piston 4 as to permit the piston to perform its maximum stroke without engaging the disk 8. This arrangement of the piston and disk permits the head of the piston to serve as a partition between the disk and the combustion end of the cylinder 1. When the piston 4 is reciprocated in the cylinder, it intermittently forms two chambers in the cylinder 1, i. e., the combustion chamber 11 and the auxiliary chamber 7.

In order to utilize the advantage gained by the provision of the auxiliary chamber 7, the skirt 4a of the piston 4 has placed therein a number of openings 12, which serve as intake ports for the chamber 7. The cylinder 1 is cast with an intake opening 13 which is positioned so as to register with the auxiliary chamber 7, adjacent the disk 8. When the piston head is moved away from the disk 8, air is drawn in through the port 13, the openings 12 of the piston skirt 4a, and into the chamber 7, formed as previously explained by the space between the piston head and the disk with the walls of the skirt. When the piston head travels towards the disk 8, the pressure is reversed.

The cylinder block is so cast as to provide a chamber 14 which serves as a super-charging chamber for the engine. Figures 1 and 2 show the chamber 14 disposed above the intake port 13 and made as an integral part of the cylinder casting. The base of this casting is provided with an intake passage 15, which contains a cylindrical type of valve 16, or a rotary type of valve 16a, as shown in Figure 1. Either form of this valve functions to open and close the port 13, controlling the passage of air therethrough. The form of valve 16 may be made similar to a piston type of valve having a body portion 17 and a rigid stem 18. In this form of valve construction and as shown in Figures 2 and 3, an air passage 19 is interposed between the intake passage 15 and the lower end of the chamber 14. One end of the piston-type valve

16 seats in the air passage 15 and the other end of the valve seats in the lower end of the chamber 14. The valve 16 is so formed that its body portion 17 projects through the air passage 19 and it is positioned, relative to the seats of the chamber 14 and the passage 15, so that it will intermittently open and close the openings thereof. The valve 16 may be timed so that air may be intermittently drawn into the chamber 7 and then forced into the chamber 14.

The rotary-type of valve 16-a, shown in Figure 1, serves the same purpose as the valve construction 16, but in the operation of the valve 16-a, it may be driven by gears or a train of gears, by means of a chain A and the sprockets B and C. The gear C is supported on the crank-shaft 3 and the gears B and C are of such diameters as to drive the rotary valve 16-a at one-half crank-shaft speed, and in timed relation with the opening and closing of the intake port 13 and air passage 15.

The head 20 of the cylinder block or casting may be secured to the cylinder 1 in the conventional manner. This head consists of an injector 21, an exhaust valve 22, and an intake valve 23. Each of these valves, as well as the valve 16, may be constructed similar to the conventional type of valves used in internal combustion engines and actuated by a cam shaft or cam shafts that are geared to the crank-shaft 3 of the engine, in connection with the stem or stems 18. It is obvious that the head of the engine may also be provided with glow plugs, spark plugs, and other units used in engines (not shown.) The intake valve 23 of the head 20 is positioned so as to seat in the passage of the air from the chamber 14 to the combustion chamber 11 of the engine.

In Figure 3 is illustrated a further modification of the invention, in which the initial intake of air to the auxiliary chamber 14 is disposed on the opposite side of the cylinder 1 relative to the chamber 14. This variation in the structure necessitates the use of an intake valve 26 which is not an integral part of the valve 16, as shown in Figure 2. An intake chamber 27 is formed on the side of the cylinder 1 and provided with a lateral port 28 which registers with a plurality of openings 29 which are provided in the jacket or skirt of the piston 4. This chamber 27 is provided with an adjustable piston 30 which may be moved to vary the capacity of the chamber 27. When the piston 4 is moved from the disk 8, air will pass through the valve 26 and into the auxiliary chamber 7. When the piston travels in the reverse direction, air will be forced out of the chamber 7, through the ports 12, 13, into passage 19, through valve 16' and into the chamber 14.

The base of the chamber 14, in this form of variation is formed so that the stem of the valve 16' passes through the passage 19 and the valve 16' is opened only when the piston 4 is on its downward stroke. By placing the initial intake valve regulating the pressure to the chamber 7 on the side of the cylinder 1 and opposite the chamber 14, permits sufficient space for the provision of mechanism for varying the pressure of the engine. The piston 30 may be automatically controlled or manually adjusted for varying the capacity of the passage 21a. The purpose of chamber 27 is to vary the supercharging or to make a predetermined supercharging of the engine by retaining part of the mixture in cham-

ber 27 thereby reducing the vacuum of the suction pump, the contents of which when compressed into the container 14 will be one volume or any portion greater than one volume which may be desired.

The passage in the chamber 27 is open and provided with a cap 31 which may be bolted thereon. The piston 30 is provided with a rod 32 which projects through the cap 31. The rod may be threaded and a nut 33 screwed thereon and against the cap 31 for holding the piston 30 in the desired position in the chamber 27.

In addition to the intake chamber 27 with its piston 30 there is also placed on the wall of the chamber 14 a small cylinder 34 with a piston 35 for controlling the volume of cylinder 14. These elements may also be used with the construction of engine shown in Figure 1.

While the disclosure presents a practical working embodiment of an internal combustion engine embodying the invention, including the variations shown, it is to be understood that the structure may be further modified in keeping with the inventive thought thereof, and which modifications would be within the scope and meaning of the claims appended hereto.

What is claimed is:

1. A four-cycle internal combustion engine comprising a cylinder having a reciprocating piston therein, said piston including a skirt portion, a stationary member disposed within the skirt portion of said piston and adapted to form an auxiliary chamber within said skirt portion, ports disposed in the skirt portion of said piston and said cylinder for passage of air into said auxiliary chamber, a container disposed in operative relation with said cylinder, means for directing said air from said auxiliary chamber into said container, and means for releasing said air from said container into said cylinder whereby the air will supercharge said cylinder for scavenging and combustion purposes.

2. A four-cycle internal combustion engine comprising a cylinder having a reciprocating piston therein, said piston having a uniform hollow extension open at one end, a member rigidly disposed in the extension of said piston and adapted to form an auxiliary chamber in said piston, a container operatively disposed relative to said cylinder, and ports and valves operatively disposed relative to said cylinder, auxiliary chamber and the container, whereby the movement of said piston will function to take in a medium into said auxiliary chamber, compress said medium into said container, and then admit the medium into said cylinder for combustion purposes.

3. A four-cycle internal combustion engine comprising a cylinder having a reciprocating piston operatively disposed therein, said piston having a hollow skirt, a stationary member within the skirt of the piston, the skirt of said piston being adapted to telescope over the stationary member for forming an auxiliary chamber in said piston skirt, a second cylinder operatively disposed relative to said first cylinder, means for drawing a medium into said auxiliary chamber, forcing the same into the second cylinder, and then admitting same into the first named cylinder for combustion purposes; including means for adjusting the volume of said second cylinder to regulate the scavenging and charging pressure thereof.

4. A four-cycle internal combustion engine as

claimed in claim 3, wherein said means for adjusting the volume of said second cylinder consists of a chamber formed adjacent to the piston cylinder, said chamber having a lateral opening and being provided with a piston and a valve, a port communicating with said chamber and the piston cylinder, and a plurality of ports in the

wall of the piston skirt adjacent the chamber.

5 5. A four-cycle internal combustion engine as claimed in claim 3, wherein said stationary member is adapted to be mounted rigidly to either the crank-case or to an extension of the cylinder block of the engine.

NOBLE P. SHERWOOD.
